J. MORRISON

SEMITRAILER JACK

Filed April 19, 1920

UNITED STATES PATENT OFFICE.

JAMES MORRISON, OF CINCINNATI, OHIO, ASSIGNOR TO THE TRAILMOBILE COMPANY,
OF CINCINNATI, OHIO, A CORPORATION OF OHIO.

SEMITRAILER JACK.

Application filed April 19, 1920. Serial No. 374,882.

To all whom it may concern:

Be it known that I, JAMES MORRISON, a citizen of the United States, and a resident of the city of Cincinnati, in the county of 5 Hamilton and State of Ohio, have invented certain new and useful Improvements in Semitrailer Jacks, of which the following is a full, clear, and exact description, reference being had to the drawings forming a 10 part of this specification.

My invention relates to jack devices for semi-trailers and more particularly to mechanism for simple and effective conjoint operation of a pair of jacks one for each side of 15 a vehicle.

In semi-trailer vehicles, wherein the semi-trailer is supported at its forward end upon the tractor, it is an extremely essential part 20 of the mechanism to provide an effective means of maintaining the front end of the trailer in elevated position when the tractor has been drawn out from beneath it.

According to the invention herein I employ as the jack elements of the device a pair 25 of screw jacks the upper ends attached to the trailer, and the other ends fitted with a hinged leg, for contact with the supporting surface, but it is to the mechanism provided for swinging the jack legs upwardly 30 on their hinges, that my invention in this application is directed.

In this mechanism the object is to quickly and easily lift up the said hinged legs, or any other type of suspended jack device, and 25 to provide for operation from either side of the vehicle.

These objects and other advantages to be noted I accomplish by that certain construction and arrangement of parts to be herein- 40 after more specifically pointed out and claimed.

In the drawings,

Figure 1 is a detail elevation showing the jack raising device.

Figure 2 is a general view in elevation.

Figure 3 is a detail longitudinal section illustrating the ratchet mechanism in a simpler form. Figure 4 is a detail elevation of the parts shown in Figure 3.

The jack which is used with my lifting mechanism is merely the selected one for purposes of illustration, as the mechanism

could be readily adapted for the raising of any kind of jack devices which are suspended from a vehicle.

As shown, the frame 1 of the trailer is equipped with internally threaded jack members 2, in which are set the jack screws 3. The screws are operated by means of any suitable pawl and ratchet device, utilizing 60 operating handles 4, and are right and left hand threaded.

The lower jack members 5, threaded internally to receive the jack screws, are equipped with legs 6, hinged thereto at 7, 65 and locked in operative position by means of dogs 8.

The legs are equipped with feet 9, which do not permit of revolution of the legs, and when the load is supported on the feet and 70 legs, and the jack screws revolved, the result will be a thrust exerted against or relaxed toward the load. When there is no load on the legs they may be readily turned by hand, so as to make preliminary adjustments thereof along the screws, and so as to provide for horizontal supporting of the vehicle on an uneven supporting surface.

The pull for raising the hinged legs of the jacks, is exerted through a chain 10, which 80 is loosely mounted on the jack legs by means of rings 11, mounted thereon along with the feet.

Across the trailer frame, preferably to the rear of the jacks is journaled, by means of brackets 12, a slideable and rotatable shaft 13.

At interspaced points inside of the frame lines of the vehicle, the shaft is equipped with a pair of rigid arms or cranks 14, at the outer ends of which are hooks 15, for engaging the lifting chains. Due to the fact that the jacks may readily rotate when the load is relieved, the legs can be lifted inwardly and upwardly of the frame, thereby moving them entirely out of the way.

The revolution of the shaft 13 will accomplish this lifting in a very efficient manner, since the first quarter turn of the shaft provides a considerable motion of the hinged legs, with the pull exerted on a line substantially of the same arc as the arc of movement of the legs. Continued shaft revolution then winds the chains up on the shaft, with no chance of the chain slipping off, as

on a reel, and with the even wrapping of the chain insured due to the slanting line of pull.

Furthermore the shaft may be provided with an operating device on both ends thereof, so as to make it operable from either side of the vehicle.

The bracket journaling device at one side of the vehicle is provided with a disk portion 16, cut with radial facial teeth 17. The operating handle 18 at this end of the shaft is secured fast thereon, and is provided with a like disk 19, having facial teeth 20.

The other end of the shaft is provided with a rigid handle 21, properly located inside of its end, and the ends of the shaft are both equipped with loosely mounted hand hold sleeves 22, held in place between the operating handles and terminal collars 22^a.

Located on the shaft inside of the trailer frame is a fixed collar 23, between which and the frame is mounted a spring 24. This spring tends to draw the shaft in a direction to cause a meshing between the facial teeth of the two disks.

A pull on the one hand hold or a pressure on the other will overcome the action of the spring, and permit the shaft to turn, as soon as the two disks are forced out of mesh. The spring will give in the operation of the handles on the shaft, to permit ratchet action, the teeth having suitably sloped faces.

In operating the raising device, the hinged legs of the jacks are first freed of the load, and then either handle 18 or 21 may be revolved to and fro, and around, so as to wind up the chains. To let the legs down again the operator pulls on one of the hand holds or presses inwardly on the other, so as to permit the shaft to revolve freely and permit the legs to swing down of their own weight.

As can be appreciated the raising of the jacks toward the center of the trailer cooperates with the screw type of the jack to make a simple and effective mechanism, which permits the jacks to be lifted out of the way toward the inside of the trailer frame, and entirely withdrawn and with the chains wound over a shaft, and not a reel.

A considerably simpler form of ratchet device for operating the shaft 13 is shown in Figures 3 and 4, wherein the rigid member 16 that is mounted on the trailer frame corresponds to the member 16 hitherto described.

The difference is, however, that the teeth 17^a for this member are V-shaped. The handle 18^a is the same as the handle 18 and is likewise pinned to the shaft 13 and carries toothed plate 19.

The teeth 20^a, however, are also V-shaped so as to mesh with the teeth 17^a.

In this construction the hand hold members 22 are entirely omitted, and in raising and lowering the jacks the handle 18^a must be manipulated.

The spring 24 is of sufficient strength to hold teeth 17^a and 20^a in mesh when the jacks are raised.

When the handles on either end are manipulated, however, the teeth will snap out of mesh without excessive resistance.

Thus this device is considerably simpler in form, although it is not so positive a lock nor so rapid in operation when it comes to lowering the jacks.

It will be understood that the parts described are illustrative of my invention and not intended as bounds whereby the scope of my invention is to be limited.

Having thus described my invention, what I claim as new and desire to secure by Letters Patent, is:

1. A device for swinging up the jacks in semi-trailers, comprising a shaft, elements extending from said shaft intermediate its ends, flexible connections from said elements to the jacks, with said elements located with reference to the jacks, such that the flexible elements wind up on the shaft, outside of the extending elements.

2. A device for swinging up the jacks in semi-trailers, comprising a shaft, elements extending from said shaft intermediate its ends, flexible connections from said elements to the jacks, with said elements located with reference to the jacks, such that the flexible elements wind up on the shaft, outside of the extending elements, and means for rotating the shaft from either end thereof.

3. A device for swinging up the jacks in semi-trailers, comprising a shaft, elements extending from said shaft intermediate its ends, flexible connections from said elements to the jacks, with said elements located with reference to the jacks, such that the flexible elements wind up on the shafts, outside of the extending elements, means for rotating the shaft from either end thereof, a ratchet lock for the shaft, and means at either end of the shaft for releasing said ratchet.

4. A device for swinging up the jacks in semi-trailers, comprising a shaft mounted on the vehicle, elements extending from said shaft intermediate its ends, flexible connections from said elements to the jacks, a fixed toothed member on the vehicle, a matching toothed member on the shaft, means for resiliently mounting the shaft on the vehicle, so as to slide with reference thereto, and means loosely engaging the shaft and serving for manual engagement to shift the shaft slidably, thereby releasing the engagement of said disks.

5. A device for swinging up the jacks in a semi-trailer, comprising a shaft mounted

across the frame of the vehicle, a pair of arms on the shaft located within the vehicle frame, operating arms for the shaft located exteriorly of the vehicle frame, and flexible connections from the inner arms to the jacks, for the purpose described.

6. A device for swinging up the jacks in a semi-trailer, comprising a shaft mounted across the frame of the vehicle, a pair of 10 arms on the shaft located within the vehicle frame, operating arms for the shaft located exteriorly of the vehicle frame, and flexible connections from the inner arms to the jacks, said shaft being resiliently mounted to slide 15 with relation to the vehicle frame, and means on the vehicle frame to limit the rotary movement of the shaft in one direction, said

means being releasable from the shaft by the lateral sliding thereof.

7. A device for swinging up the jacks in 20 semi-trailers, comprising a shaft on the vehicle frame, slidably and rotatably mounted means for revolving the shaft, means on the shaft for engaging a flexible member, said flexible member being adapted for connection with the jacks, a ratchet device intermediate the shaft and the vehicle frame, means for resiliently holding the shaft in ratchet engagement position, and hand holds on the shaft for moving it away from ratchet 25 engagement position, while permitting free revolution of the shaft.

JAMES MORRISON.
